ATTORNEY

UNITED STATES PATENT OFFICE.

EDGAR M. CRAIG, OF MARTINSBURG, IOWA.

WIRE-CLAMP.

1,250,096.

Specification of Letters Patent. Patented Dec. 11, 1917.

Application filed September 7, 1917. Serial No. 190,195.

To all whom it may concern:

Be it known that I, EDGAR M. CRAIG, a citizen of the United States, residing at Martinsburg, in the county of Keokuk and 5 State of Iowa, have invented certain new and useful Improvements in Wire-Clamps, of which the following is a specification.

This invention relates to wire clamps, and particularly to clamps for use in holding 10 and stretching woven wire fences, having for its primary object to generally simplify and improve the construction and operation of such devices, as well as to increase the efficiency of the same.

15 A further object of the invention is to provide a clamp for use in the stretching operations of woven wire fabrics which may be quickly and easily applied to the fence fabric, or removed therefrom, and which 20 holds the fabric firmly when once applied thereto.

Still further objects reside in providing a clamp of the character set forth which shall be of extremely simple and inexpensive construction, which is composed of but few simple and readily assembled parts, all of which are so constructed and assembled as to minimize the opportunity for wear or breakage, which is capable of being manipulated 25 by one man, and which will prove thoroughly efficient and practical in use.

With these objects in view together with others which will appear as the description proceeds, the invention resides in the novel 30 formation, combination and arrangement of parts, all as will be described more fully hereinafter, illustrated in the drawing, and particularly pointed out in the claims.

In the drawing:

40 Figure 1 is a side elevation of a wire clamp constructed in accordance with the invention.

Fig. 2 is a view similar to Fig. 1, and illustrating the reverse side of the clamp,

45 Fig. 3 is a sectional view taken substantially upon line 3—3 of Fig. 1, and

Fig. 4 is a view taken upon line 4—4 of Fig. 2:

Fig. 5 is a perspective view of the lock-bolt and head.

In carrying out the invention, I employ a pair of clamp bars, the same being in the present instance of equal length, width and thickness, and these bars may be formed 55 of any desired material. These bars are indicated at 5 and 6, respectively; the former

bar carrying the locking elements which are adapted to engage within suitable apertures in the bar 6 to hold the latter firmly engaged with the said bar 5.

Rotatably mounted in spaced parallel relation throughout the length of the bar 5 are locking bolts 7. These bolts extend transversely through the bar 5, and protrude an appreciable distance beyond the side thereof, the exposed portions of the said lock bolts being of increased diameter, as shown, to limit the inward sliding movement of the said bolts. The opposite ends of the bolts are each equipped with a crank-arm 8, 70 the said arms being firmly secured and held upon the bolts by the retaining nuts 9. The outer extremities of the crank-arms 8 are pivotally connected with a rod 10, so that longitudinal movement of the rod will cause all 75 of the lock bolts to rotate in unison.

Arranged upon the outer surface of the bar 5 and at one end thereof is a longitudinally disposed rack-bar 11, over which a clevis 12 slides. This clevis has pivoted thereto a lever 13, one end of which is bent laterally to provide a pin 14 engaged with one end of a link 15, the opposite end of the said link being pivotally connected with the longitudinally disposed bolt-operating rod 85 10. The clevis 12 is capable of being freely slid over the rack-bar 11, but will be held by the teeth of the rack-bar against reverse sliding movement. When it is desired to rotate the lock-bolts 7, the lever 13 will be 90 rocked upon its pivot, and this movement will be transmitted to said lock-bolts through the link 15 and rod 10.

The bar 6 is provided with a plurality of spaced transverse openings 16, one opening 95 being provided for each of the lock bolts 7 carried by the opposite bar. These openings are of a diameter sufficient to accommodate the enlarged ends of the locking bolts 7, and the outer surface of the bar 6 is provided 100 with a number of metallic plates 17, one of which is arranged over each of the openings 16. The central portion of each plate is depressed, as shown particularly in Figs. 3 and 4 of the drawing, the said depressed portions extending into the openings 16, and the metal constituting the bottom of each depressed portion is provided with an elongated opening 18. These openings are adapted to receive the laterally disposed 110 heads 19 upon the outer ends of the lock bolts 7, the said heads being of a length and

width substantially equal to the length and width of the said openings. As shown in the drawing, the openings 18 of the various plates 17 are disposed longitudinally of the bar 6 and it is obvious, therefore, that the heads 19 of the locking bolts can only enter into these openings when the said heads are disposed longitudinally of their supporting bar 5.

10 The opposing edges of the heads 19 at the opposite ends thereof, may be beveled or cut away as indicated at 19' so as to ride upon the inclined edges of the metal defining the opening 18 in its plate 17. The inclined edges of the said plate are indicated at 18', and it is obvious that such arrangement permits of the ready manipulation of the same and obviates the possibility of binding of the head 19 within the opening.

20 In applying the clamp to a fence fabric, the bars 5 and 6 are separated, and are placed one upon each side of the fabric. The bolts 7 at their enlarged ends project through the mesh fabric, and the lever 13 is operated so 25 that the heads ends of the said lock bolts are disposed longitudinally. When in this position, the said heads will enter the elongated openings 18 in the depressed portions of the plates 17 of the bars 6, and after being so 30 inserted in said openings, the lever 13 is swung inwardly upon the bar 5. This action of the lever causes the rod 10 to move longitudinally of the bar 5, whereupon the crank-arms 8 cause the lock-bolts 7 to rotate so 35 that the heads 19 at the outer ends thereof will be disposed laterally of the bar 6. When so disposed, the said bars will be firmly locked together, and can only become detached when the rod 10 has been moved in 40 a reverse direction.

To assist in holding the bars 5 and 6 together, and to enable the clamp to be attached to a stretching apparatus, one of the bars has hinged at its opposite ends loops 20. 45 These loops are hinged in the present instance to the bars 6, as indicated at 21, and are of dimensions sufficient to enable the said loops to be swung over and to inclose the adjacent end of the opposing bar 5. 50 Each of these loops is provided with a hook 22, to which a suitable draft or stretching apparatus may be secured.

From the foregoing it is obvious that I

have provided an extremely simple and thoroughly efficient clamp for holding fence 55 fabrics during the stretching operation. After the bars have been properly positioned upon the opposing surfaces of the wire and the lever 13 has been properly operated, the said bars will be securely held against becoming separated, and the loops 20 at the ends of the bars assist in holding the latter 60 securely together.

While the present disclosure is that of what is believed to be the preferred embodiment of the invention, it is to be understood that changes in the minor details of construction, proportion and arrangement of parts 65 may be resorted to if desired without departing from the spirit of the invention as 70 defined by the appended claims.

What is claimed is:

1. In a wire clamp, a pair of clamp bars, one of said bars having laterally disposed apertures, lock bolts extending through the 75 other of said bars and being adapted to engage in said apertures, the said bolts being adapted when rotated to a certain degree to lock said bars together, a crank-arm on each bolt, a rod common to all of said arms, a rack 80 bar, a clevis adjustable upon said rack bar, a lever pivoted upon said clevis, and a rod connecting said link and lever.

2. In a wire clamp, a pair of clamp bars, a plurality of laterally disposed lock bolts on 85 one of said bars, laterally extending heads on the outer ends of said bolts, the other of said bars having transversely extending openings adapted to receive said bolts, the said openings being restricted at one end 90 and being adapted to receive said heads only when said bolts have been rotated to a certain degree, a crank-arm on the inner end of each bolt, a rod connecting all of said arms, a rack bar on said bolt carrying bar, 95 a clevis adjustable on said rack bar, a lever pivoted on said clevis, a link connecting said lever and rod, and hook loops hinged to one of said bars and being adapted to inclose the 100 opposite bar.

In testimony whereof I affix my signature in presence of two witnesses.

EDGAR M. CRAIG.
